FISH LURE

Segurd B. Bekkala, Northville, Mich.

Application May 6, 1948, Serial No. 146,206

Term of patent 14 years

(Cl. D31—4)

To all whom it may concern:

Be it known that I, Segurd B. Bekkala, a citizen of the United States, residing at Northville, in the county of Oakland and State of Michigan, have invented a new, original, and ornamental Design for a Fish Lure, of which the following is a specification, reference being had to the accompanying drawing, forming a part thereof.

Fig. 1 is a rear quarter perspective of a fish lure, showing my new design;

Fig. 2 is a sectional view of the forward portion of the lure, taken on line 2—2 of Fig. 1;

Fig. 3 is a sectional view of the rear portion of the lure, taken on line 3—3 of Fig. 1; and

Fig. 4 is a sectional view of the lure taken on the longitudinal center line taken on line 4—4 of Fig. 1.

I claim:

The ornamental design for a fish lure, as shown.

SEGURD B. BEKKALA.
